DESIGN FOR A FOUNTAIN PEN BARREL

Warren Green, Noroton Heights, Conn., and Peter Schladermundt, Bronxville, N. Y., assignors to Stratford Pen Corporation, New York, N. Y., a corporation of New York

Application December 14, 1946, Serial No. 135,501

Term of patent 14 years

(CL. D74—17)

To all whom it may concern:

Be it known that we, Warren Green and Peter Schladermundt, both citizens of the United States, residing in Noroton Heights, county of Fairfield, and State of Connecticut, and Bronxville, county of Westchester, and State of New York, respectively, have invented a new, original, and ornamental Design for a Fountain Pen Barrel, of which the following is a specification, reference being had to the accompanying drawing, forming a part thereof, wherein:

Fig. 1 is a front view of a fountain pen barrel, showing our design;

Fig. 2 is a side view of the fountain pen barrel;

Fig. 3 is a rear view of the fountain pen barrel; and

Figs. 4, 5 and 6 are cross sectional views in the direction of the arrows on the lines 4—4, 5—5 and 6—6 respectively, of Fig. 1.

The essential features of our design are shown in full lines.

We claim:

The ornamental design for a fountain pen barrel, substantially as shown and described.

WARREN GREEN.

PETER SCHLADERMUNDT.
